UNITED STATES PATENT OFFICE.

WILLIAM J. LAUSTERER, OF JAMESTOWN, NEW YORK, ASSIGNOR TO THE U. S. STANDARD VOTING MACHINE COMPANY, OF ROCHESTER, NEW YORK, A CORPORATION OF NEW YORK.

VOTING-MACHINE.

No. 849,001.

Specification of Letters Patent.

Patented April 2, 1907.

Application filed October 6, 1905. Serial No. 281,610.

To all whom it may concern:

Be it known that I, WILLIAM J. LAUSTERER, of Jamestown, in the county of Chautauqua and State of New York, have invented certain new and useful Improvements in Voting Machines; and I do hereby declare the following to be a full, clear, and exact description of the same, reference being had to the accompanying drawings, forming a part of this specification, and to the reference-numerals marked thereon.

This invention relates more particularly to that type of voting-machine in which a movable register-frame is used, such as is described in the patents of A. J. Gillespie, in which the vote is first indicated by placing in voted position a plurality of keys or indicators, each indicating the vote for its respective candidate, all of which votes are registered simultaneously by the movement of the register-frame.

My invention relates more particularly to a device for connecting the middle or part intermediate the ends of the register-frame to the part of the face-plate opposite thereto, so that any tendency on the part of either the register-frame or the face-plate to spring between the operated ends is counteracted and prevented and the parallelism of the parts is maintained.

In the accompanying drawings, Figure 1 is a detailed perspective view showing the rear side of the front plate and the moving register-frame of the machine. Fig. 2 is a perspective detail showing the coupling between the middle of the register-frame and the face-plate.

Similar reference-numerals in the several figures indicate similar parts.

The machine-casing so far as shown embodies the face-plate or ballot-board 5, on which the ballot-indicators 27 are mounted, the side plates 6, one only being shown, and a bar 7, extending across the rear of the casing. The register-frame (indicated by 1) embodies the top and bottom plates 3 and 4, connected by the end bars or plates 34, and extending between the plates 3 and 4 are the channels 2, containing the registers, each register having a pallet-bar or actuator 29, adapted to be connected to its actuator and operated when the plate and frame are moved toward and from each other. Any

suitable means may be employed for causing this relative movement—such, for instance, as the vertically-movable pivoted levers 35, having studs or rollers operating in the slots 36 of the end bars or plates 34.

8 indicates a rod or link pivotally connected at one end to the bar 7 and at its other end connected to one arm of a horizontal bell-crank 9, pivoted at 30 to the under side of the bottom plate 4 of the register-frame, the other arm of said bell-crank being pivoted to the end of a link 10. This link 10 extends along under the plate 4 and engages with the vertically-extending arm of a bell-crank 11, pivoted under the plate 4, and has pivotally connected to its other arm the vertically-moving rod 12, passing through an aperture in the plate 4, and its upper end passes through bearings in a suitable guide 13. Formed upon or, as shown, cut in the side of said rod 12 is a rack 14, which engages with the pinion 15, carried in suitable bearing or brackets 16 integral with the guide 13. The shaft 17 of the pinion 15 extends horizontally parallel with the face-plate of the machine, being mounted at its ends in vertically-extending plates or supports 28, secured to the register-frame between the register-channels 2, and the pinion 15 is broad enough, so that another rack 18 can be engaged therewith and be free to move transversely to the rod 12. The bracket 16 of the pinion 15 is made U-shaped, so as to support the rack 18 and hold it in engagement with the pinion. At the outer end of the rack 18 is provided a stud 19, which engages with a slot 20, cut in a plate 21, rigidly attached to the face-plate of the machine. This plate may be secured in any suitable manner; but I prefer to provide it with lugs 25, extending through suitable apertures in the front plate, which lugs may be headed over to secure them, the shoulders 26 being seated against the rear side of said plate.

The parts are so proportioned and arranged that as the register-frame moves forward the rod 12 and the rack 18 move sufficiently to permit and compel the middle of the frame to move just as far as does the end of it, and through its connection with the front plate the front plate is prevented from springing away from the counter-frame when the frame is moving toward it and from fol-

lowing the register-frame when the latter is moving away from it. In this way complete operation of all the pallet-bars is secured whether they are all operated directly 5 from the indicators on the front plate or through the medium of the indorsing bars or connections between them. As the register-frame moves forward toward the front plate the bell-crank 9 will be rocked by reason of its connection with link 8. This will in turn move the link 10 to the right and will, through the bell-crank 11, drive the rod 12 up and will rotate the pinion 15 through the rack 14. The pinion 15 will in turn communicate its motion to the rack 18, which in turn will draw on the plate 21 and the front plate of the machine to which it is connected, thus preventing it from springing away materially from the register-frame as the 15 counter-frame advances toward it. As the register-frame moves away from it the reverse movement of the parts takes place, and then the rack 18 will prevent the front plate from following the frame, so that in both the 20 forward and back movement of the counter-frame the pallet-bars will be properly operated on by the indicators carried on the front plate of the machine.

While my invention contemplates the employment of other means for maintaining the parallelism of the plate and frame during their relative movements, the form herein shown is particularly applicable to machines now in use, as it can be applied without 25 modification or change of the parts, the plates or supports 27 extending between the register-channels, the bell-cranks being arranged beneath the register-frame and the pinion and between the registers and the 30 front plate.

I claim as my invention—

1. In a voting-machine, the combination with a plate, the register-frame and means operating upon the ends of the plate and 45 frame for causing their movement relatively toward and from each other, of connections between the plate and frame at their ends and connections intermediate their ends connected for simultaneous operation to maintain the parts parallel during 50 their movements.

2. In a voting-machine, the combination with a plate, the register-frame and means for causing their movement relatively toward and from each other, of means auxiliary to said operating means and connecting the plate and frame at a different point for maintaining the parallelism of the parts of the frame and plate.

3. In a voting-machine, the combination of a plate bearing indicators, a relatively movable register-frame, registers thereon and pallet-bars for operating the registers, and with which the indicators coöperate 65 and the positive connection between the

frame and the plate preventing a springing of either member during the movement of the parts.

4. In a voting-machine, a stationary plate and a relatively movable register-frame, 70 means for causing relative movement between them and connections at the middle of said register-frame and plate to hold that portion of the plate and the frame in the same relative positions as the ends. 75

5. In a voting-machine, a plate, a movable register-frame, connections between the ends of the plate and frame for moving them relatively toward and away from each other, connections between said plate and said frame at a point intermediate of the ends coöordinating with the connection at the ends for the purpose of moving said parts uniformly at all points of connection. 80

6. In a voting-machine, the combination 85 with the casing, the plate, the relatively movable register-frame, a bell-crank pivoted on the frame and having one arm connected to the casing, and a rack connected to the other arm, of a rack connected to the plate 90 and gearing and a gear arranged between said racks for causing equal parallel movement of the plate and frame.

7. In a voting-machine, the combination 95 of the casing, the plate, the relatively movable register-frame, two bell-cranks pivoted on the frame and operating at right angles, a link extending between said bell-cranks and connections between one of said bell-cranks and the frame and between the other 100 and the plate for causing relatively equal and parallel movements of the parts.

8. In a voting-machine, the combination of the casing, the plate, the relatively movable register-frame, racks connected to and 105 moving with each of the parts, a pinion between the racks and connections between the register-frame and the casing for moving one of the racks as the frame is moved.

9. In a voting-machine, the combination 110 with the relatively movable plate and register-frame, of a horizontally-extending rack connected to the plate, a vertically-movable rack connected to the frame, the pinion between them and means for actuating the 115 vertical rack relatively to the frame when the latter is moved relatively to the plate.

10. In a voting-machine, the combination with the relatively movable plate and register-frame, of the horizontal rack extending 120 rearwardly from the plate, the vertically-movable rack on the frame, the pinion between them, the bell-crank on the frame movable in a vertical plane and connected to the rack, the bell-crank movable in a 125 horizontal plane connected to the first-mentioned bell-crank and mediate to the plate.

11. In a voting-machine, the combination with the relatively movable plate and register-frame, the register-casings on the latter, 130

and the support independent of the channels, of the horizontal rack on the plate; the pinion journaled on the support, and meshing with the rack, the vertical rack on the frame also meshing with the pinion and connections intermediate said rack and the plate for causing the reciprocation of the former when the plate and frame are moved relatively.
